CONTAINER

Wallace C. Mills, Rockford, Ill., assignor to J. L. Clark Manufacturing Co., Rockford, Ill., a corporation of Illinois

Application October 13, 1932, Serial No. 637,571

15 Claims. (Cl. 221—11)

The invention pertains to containers for condiments and the like, and has especial reference to a container having pouring and sifter holes adapted to be covered or uncovered by a slide mounted in the top wall of the container.

One object of the present invention is to make provision for a pouring spout adapted for use in conjunction with the pouring opening when the slide is in a position to cover the sifter holes, and thereby facilitate the removal of the contents of the can by pouring.

A further object is to provide a container equipped with a sifter slide and a pivotal pouring spout cooperating in a novel and effectual manner to permit the contents of the container to be removed by sifting or pouring selectively, as well as to close both sifter and pouring openings.

Another object is to provide a container having a sifter slide with sifting and non-sifting positions, and a swingable pouring spout adapted to be locked in closed position by the slide when in either of said positions.

Still another object is to provide a pivotal pouring spout capable of being quickly and easily assembled and mounted in a manner such as to avoid interference with the sifting slide.

The objects of the invention thus generally stated together with other and ancillary advantages, are attained by the construction and arrangement illustrated in the accompanying drawing forming part hereof in which

Figure 1 is a perspective view of my improved container and illustrating the pouring spout in operative position.

Fig. 2 is a fragmentary perspective view illustrating the construction of the spout and the method of hinging the same, the spout being shown in detached relation to its support.

Fig. 3 is a fragmentary perspective view showing the spout assembled on its support and in partially open position.

Fig. 4 is a top plan view of the container with one end of the sifter slide broken away to show the hinged end of the spout in its closed position.

Fig. 5 is a fragmentary vertical sectional view taken in the plane of line 5—5 of Fig. 4.

Fig. 6 is a fragmentary perspective view showing a modified form of spout with the latter in open position.

The container comprises, in the embodiment illustrated, a body 7 having an upper end or top wall comprising a top plate 8 secured to the upper edge of the body in any suitable way as by means of a seam 9. The top plate 8 is aper-

tured to provide a relatively large opening of oval shape, defined by an upstanding rib 10 having a down-turned friction flange 11. Into this opening is frictionally fitted a removable cover, generally designated 12, to complete the top wall. 60

The cover 12 comprises a flat plate 13 with a vertical side flange 14 adapted to engage with the flange 11 of the top plate. The upper edge of this flange 14 terminates in a lateral bead 14^a in the form of an inwardly opening fold, 65 which bead forms a stop on the cover for engagement with the rib 10 on the top plate.

The cover plate 13 is provided with a series of sifter holes 15 and a pouring hole 16; and mounted to slide upon the plate 13 exteriorly thereof, 70 is a slide plate 17 having a series of sifter holes 18 and a pouring hole 19. This plate is retained in position upon the cover plate 13 by means of a pair of laterally extending guide flanges or tongues 20 on opposite sides of the slide, engaging in channel-shaped guides 21 formed at the upper edge of the flange 14 of the cover at opposite sides thereof. The guide flanges 20 are formed at the upper edge of an upstanding flange 22 on the slide plate 17; and the channel shaped 80 guides 21 are formed by raising the upper part of the fold which forms the bead 14^a on the cover plate 13, as indicated at 23.

The pouring opening 16 in the top plate is in the form of an elongated slot, and mounted on 85 the top plate for swinging movement through said slot is a pouring spout generally designated 24. This spout comprises an end wall or closure plate 25 and two segmental side walls 26. One end of the wall 25 is extended to form a finger piece 27, and at the other end is formed a transverse slot 28 (Fig. 2) adapted to receive a tongue 29 projecting inwardly from one end of the slot 16. The tongue is made of a width somewhat less than the slot so as to form notches 16^a (Fig. 95 4) at each side of the tongue. One edge 30 of the slot 28 constitutes a bearing edge which engages with an abutment 31 formed by a boss struck up from the tongue 29, the parts being maintained in this position by the arcuate edges 100 32 of the side walls 26 of the spout engaging with the opposite end of the slot 16 (Fig. 3). Thus the spout is adapted to swing on an axis defined by the edge 30 of the slot and the abutment 31.

Upward swinging movement of the spout is limited by triangular lugs 33 formed on and projecting outwardly from the lower corners of the side walls 26; and to permit of the easy assembling of the spout in the top plate 13, these lugs 33 are beveled as indicated at 34. Thus, in as- 110

sembling the spout, it is only necessary to pass the slot 28 therein over the tongue 29 and then force the side walls 26 inwardly until the lugs 33 move past the side edges of the slot 16, the beveled surfaces 34 of the lugs engaging with said side edges of the slot 16 with a cam action. This avoids any undue springing of the metal of the side walls 26 as might occur if they were forced inwardly by the fingers sufficiently to clear the 10 lugs 33.

In as much as the slide plate 17 must pass over the spout in its closed position, it is desirable that its end wall 25 be capable of lying substantially flush with the top plate 13. To this end, 15 the portion of the end wall 25 of the spout which extends beyond the slot 28 is in the present instance offset downwardly a distance corresponding to the thickness of the metal of the top plate 13 which, in the case of small containers of this 20 character, is very thin. Such downward offsetting of the metal of the end wall of the spout is effectually accomplished by extending the ends of the slot 28 downwardly a short distance into the side walls 26 and then crimping or wrinkling 25 the extreme end portion of the end wall as shown at 35 with a resulting depression thereof. The downwardly offset portion thus formed engages with the underside of the tongue 29 so as to hold the hinged end of the spout against upward or 30 outward movement.

As above indicated, the slide plate 17 overlies the spout 24 when in its closed position, and in order to permit the spout to be swung upwardly into its open position, the slide plate has its pouring opening 19 made of a size and shape corresponding to the slot 16 in the top plate. Thus, when the slide is moved to a position such as to carry the pouring openings 16 and 19 into registry, the spout may be swung upwardly by grasping 40 its finger piece 27. The latter, it will be observed, is bent at a slight angle to the end wall 25 of the spout so that in the closed position thereof, its free end projects upwardly to a point just above the upper surface of the slide plate 45 (Figs. 3 and 4). Hence, in the movement of the slide into pouring position, the finger piece rides upwardly upon the slide into a position in which it may be readily grasped by the finger and lifted to carry the spout into its open or operative position.

As shown in Fig. 5, the slide plate 17 is in an intermediate or shipping position, for in this relation of the parts, the sifter openings are closed and the pouring spout is in its closed position. The spout is locked in this position by reason of the fact that the pouring opening 19 in the slide is out of registry with the opening 16 in the top plate so that one extreme end portion of the slide overlies the hinged end portion 55 of the spout and locks it against upward swinging movement.

The pouring position of the slide is shown in Fig. 1, it having been moved to the extreme left from the intermediate position shown in Fig. 5. 60 In this position, the sifter openings remain closed but the pouring openings are in registry so that the spout may be swung upwardly into its operative position as shown, when it serves to lock the slide in its non-sifting position. On 70 the other hand, movement of the slide to the extreme opposite position (Fig. 4) carries the sifter openings 15 and 18 into registry while the pouring spout is locked by the overlying end portion of the slide.

75 In order that such overlying end portion of

the slide shall be capable of holding the spout downwardly more effectually, the end wall 25 of the spout may, if desired, be formed with a raised boss 37 spaced somewhat from its hinging edge 30. The overlying end portion of the slide engaging with this boss at a point offset from the hinging axis of the spout, exerts a downward pressure upon the spout and thus holds it in its closed position.

It will be observed that I have effectually combined a pouring spout of the pivotal or swinging type with a sifter slide without in any way interfering with the movements of the slide for covering and uncovering the sifter openings. By the particular hinge construction employed for the spout, free movement of the slide thereover is assured. In this latter connection, the boss forming the hinge abutment 31 serves the additional function of raising the corresponding end of the slide plate above the hinge edge 28 of the spout, thus avoiding any possible restriction in the movement of the slide from the pouring position to the intermediate or sifting positions.

In Fig. 6, I have shown a modified form of spout which may be employed. In this instance, 100 the spout is composed of two arcuate plates 38 and 39 disposed at an angle to each other to form the walls of the spout. The plate 38 constitutes the top wall or closure plate and is slotted to receive a downwardly offset tongue 29. 105 The other plate 39 constitutes a segmental side wall having an arcuate edge 40 for engagement with one edge of the triangularly shaped pouring opening 41. A lug 42 on the plate 39 serves to limit the upward swinging movement of the 110 spout and in the closed position thereof, the curved edge of the plate 38 is adapted to overlap slightly the corresponding edge of the opening.

I claim as my invention:

1. A container of the character set forth having an opening in one wall for the discharge of the contents of the container, a pouring spout mounted for swinging movement through said opening and adapted in one position of the spout to close said opening, and a slide mounted on said wall of the container and adapted to lock the spout in closed position, said container having sifter openings in said wall separate from the spout opening and also controlled by said slide. 115

2. A container of the character set forth having an opening in one wall for the discharge of the contents of the container, a pouring spout mounted for movement through said opening and adapted in one position of the spout to close said opening, and a slide mounted on said wall of the container and adapted to lock the spout in closed position, said wall of the container and said slide having two sets of sifter openings separate from the spout opening and adapted to be carried into and out of registry in the movements of the slide. 120

3. A container of the character set forth having an opening in one wall for the discharge of the contents of the container, a pouring spout mounted for movement through said opening and adapted in one position to close said opening and in another position to permit the discharge of the contents of the container through the spout, and sifter means including a plate movably mounted on said wall of the container independently of said spout and adapted in one position thereof to lock said pouring spout in closed position. 140

4. A container of the character set forth hav-

ing a pouring opening and sifter openings in one wall thereof, means including a plate slidably mounted on said wall and operable to open or close said sifter openings, and a pouring spout mounted on said wall in the path of said plate and swingable through said pouring opening in one position of said plate.

5. A container of the character set forth having an opening in one wall for the discharge of the contents of the container by pouring, a pouring spout mounted for movement through said opening and adapted in one position to close said opening and in another position to permit the discharge of the contents of the container through the spout, said wall of the container having a set of sifter openings therein, and a slide also having sifter openings therein and operable to carry said sifter openings into and out of registry with the sifter openings in said wall of the container, said spout being positioned in the path of said slide and being movable in one position of said slide.

6. A container of the character set forth having an opening in one wall for the discharge of the contents of the container by pouring, a pouring spout mounted for movement through said opening and adapted in one position to close said opening and in another position to permit the discharge of the contents of the container through the spout, said wall of the container having a set of sifter openings therein and a slide having a second set of sifter openings adapted in the movements of the slide to be carried into and out of registry with the sifter openings in said wall of the container, said slide having a portion operating in the sifting position thereof to lock said spout in its closed position.

7. A container of the character set forth having an opening in one wall for the discharge of the contents of the container by pouring, a pouring spout mounted for swinging movement through said opening and adapted in one position to close said opening and in another position to permit the discharge of the contents of the container through the spout, said wall of the container having a set of sifter openings therein and a slide having a second set of sifter openings adapted in the movements of the slide to be carried into and out of registry with the sifter openings in said wall of the container, said slide having a part operating in both the sifting and non-sifting positions thereof to lock said spout in its closed position.

8. A container of the character set forth having an opening in one wall for the discharge of the contents of the container by pouring, a pouring spout mounted for movement through said opening and adapted in one position to close said opening and in another position to permit the discharge of the contents of the container through the spout, said wall of the container having a set of sifter openings therein and a slide having a second set of sifter openings adapted in the movements of the slide to be carried into and out of registry with the sifter openings in said wall of the container, said slide having an intermediate position in which it is operative to close said sifter openings and to lock said spout in closed position, and two end positions in one of which the slide is operative to lock the spout in closed position and in the other of which the slide is operative to permit the swinging movement of the pouring spout into its operative position.

9. A container of the character set forth hav-

ing an opening in one wall for the discharge of the contents of the container by pouring, a pouring spout mounted for movement through said opening and having a plate adapted to close the opening, said spout being mounted on said wall with said plate substantially flush with the wall in the closed position of the spout, said wall having sifter openings therein, and a sifter plate for opening and closing said sifter openings and mounted on said wall independently of said spout for sliding movement over said closure plate of the spout.

10. A container of the character set forth having a slot in one wall for the discharge of the contents of the container by pouring, a tongue projecting into said slot at one end thereof, and a pouring spout having an end wall and an arcuate depending side wall, said end wall having a bearing edge adapted to engage with said tongue to form a hinging axis for the spout with said arcuate side wall of the spout engaging with the end of the slot opposite said tongue, and said tongue having an abutment thereon for engagement by said bearing edge of the spout cooperating with the engagement of the arcuate side wall and the opposite end of the slot to hold the bearing edge in place throughout the movement of the spout.

11. A container of the character set forth having an opening therein permitting the discharge of the contents of the container by pouring, a tongue projecting into said opening, and a pouring spout having a closure plate and two side plates, said closure plate having a slot therein to receive said tongue and said side plates having arcuate edges adapted to engage slidably with the end of the opening opposite said tongue, the portion of the closure plate underlying said tongue in the closed position of the spout being offset inwardly and crimped to take up the excess metal caused by said offset.

12. A container of the character set forth having an opening in one wall permitting the discharge of the contents of the container by pouring, a tongue projecting into said opening at one end thereof, a pouring spout having a closure plate with a bearing edge at one end overlying the tongue and an outwardly projecting boss adjacent said end, said tongue having a projection thereon forming an abutment with which said bearing edge engages, and an overlying sifter slide having an opening therein movable into and out of registering relation with the opening in said wall of the container to permit movement of said spout, said slide having one end portion bearing on said boss when in a non-registering position to hold the spout tightly closed.

13. A container of the character set forth having an opening in one wall permitting the discharge of the contents of the container by pouring, a tongue projecting into said opening at one end thereof, a pouring spout having a closure plate with a bearing edge at one end overlying the tongue, said tongue having a projection thereon forming an abutment with which said bearing edge engages, and a slide overlying said wall and having an opening therein movable into and out of registering relation with the opening in said wall of the container to permit movement of said spout, and said closure plate having its end portion opposite said bearing edge extended at a slight angle so as to receive said slide.

14. A container of the character set forth having a sifter slide and a pivotal pouring spout

mounted on one wall of the container, said slide operating while in its sifting position to lock the spout in its inoperative position, and the spout operating while in its operative position to hold the sifter slide in its non-sifting position.

15. A container of the character set forth having a pouring slot in one wall, and a pouring spout having a closure plate and two segmental side plates, said spout having a pivotal support at one end of said slot, and said side plates having laterally projecting lugs adapted in the open

position of the spout to engage laterally of the slot with the underside of said wall at the end of said slot opposite said pivotal support, said lugs being beveled laterally at their outer ends to provide cam surfaces adapted to engage opposite side edges of the slot to cause the side plates to yield laterally as an incident to the application to the side plates of an inward force when assembling the spout.
